UNITED STATES PATENT OFFICE.

WLADISLAUS RAKOWSKI, OF DAVIS, WEST VIRGINIA.

CURTAIN-SUPPORT.

1,093,884.

Specification of Letters Patent. Patented Apr. 21, 1914.

Application filed July 27, 1912. Serial No. 711,863.

To all whom it may concern:

Be it known that I, WLADISLAUS RAKOWSKI, a citizen of Germany, residing at Davis, in the county of Tucker and State of West Virginia, have invented certain new and useful Improvements in Curtain-Supports, of which the following is a specification.

My invention relates to devices for supporting portières or curtains or like hangings, and particularly to curtain or portière poles.

The primary object of my invention is to provide a very simple and effective curtain supporting pole, so constructed as to do away with the necessity of using rings, pins or like supporting devices for attaching the curtain to the pole.

A further object is to provide a construction of this character in which the curtain is supported by means of jaws formed upon the pole and which engage the upper edge of the curtain and hold the same in place.

A still further object is to provide a construction of this character in which the jaw supporting the curtain shall be entirely concealed and the pole look like an ordinary pole.

My invention is illustrated in the accompanying drawings wherein:

Figure 1 is a perspective view of my improved curtain pole in place. Fig. 2 is an under side plan view of the curtain pole, the movable jaws being one partly open and the other entirely open. Fig. 3 is a cross section on the line 3—3 of Fig. 2 but enlarged and showing the jaw closed.

Corresponding and like parts are referred to in the following description and indicated in all the views of the accompanying drawings by the same reference characters.

Referring to these drawings, it will be seen that my improved curtain pole consists of a longitudinally extending casing which may be circular but is illustrated as being rectangular in form and composed of the top member 2, the opposed side members 3 and 3^a, the fixed jaw 4 and the movable jaws 5, these members being arranged in rectangular relation, made of any suitable material and constructed in any desired manner. The ends of the rectangular curtain pole so formed are closed by caps 6, each cap being formed with a projecting shank 7 and an ornamental knob 8 at the extremity, the shank 7 being adapted to be engaged by the usual pole supporting hooks.

The caps 6 are attached to the ends of the hollow curtain pole in any suitable manner and I do not wish to be limited to any precise construction for these caps.

The under side of the pole is partly closed by a longitudinally extending fixed jaw 4 previously referred to which is only half the width of the pole, and opposed to this fixed jaw are a plurality of pivoted jaws 5. As illustrated there are two of these jaws, each pivoted between the end block 6 of the pole and a projecting lug 9 extending from the lower edge of the rear member 3^a. This lug is at least two inches long and is rigid with the member from which it projects. I do not wish to be limited to any particular means for hinging the jaws 5 to the body of the pole, but as illustrated each of the jaws 5 is provided with pintles 10 which project one into the adjacent end piece 6 and the other into the lug 9. The rear edge of each of the jaws is rounded as at 11 so as to permit the jaw to readily turn upon its pivot without obstruction from the lower edge of the member 3^a. Preferably, however, the jaws 5 move very tightly upon their pivots so that when they are turned to a curtain clamping position, they will hold in place by the friction of the ends of the jaws with the end caps 6 and with the lug 9. It will be noted that the jaws 5 are slightly narrower than half the width of the curtain pole so that a space is left between the edges of the jaws 9 and the corresponding edge of the fixed jaw 4. The edges of the pivoted jaws 5 are preferably formed with inclined intersecting cuts or grooves so as to roughen the inner edge of the jaw so that it will engage the curtain or portière and hold the same firmly in place when the jaws are closed.

The front member 3 of the pole or support is designed to be ornamented in any suitable manner and as illustrated is provided with ornamental carving. I do not wish to be limited however to any particular form of pole or any particular ornamental character for the same, or any particular material as it is obvious that the pole might be made in many different ways without departing from the spirit of the invention.

In the practical use of my invention, the jaws 5 are opened and the upper margin of the curtain inserted into the hollow interior of the pole and the jaws 5 are then closed, clamping the upper margin of the

curtain between the serrated edges of the jaws 5 and the edge of the fixed jaw 4. It will be understood of course that the movable jaws might be provided with fastening devices for holding them in place when closed. Such fastening devices may be in the form of bolts engaging the end pieces 6 or the lug 9, but I have found in practice that if the jaws move tightly enough upon their pivots and have proper wedging engagement with the curtain, no such fastening devices are needed and that the movable jaws will remain in their closed position and clamp the curtain without the necessity of these appliances. The jaws 5 may be moved by means of knobs 12.

What I claim is:

1. A curtain support including a hollow member, a fixed jaw extending longitudinally of and forming a part of one side of the hollow member, a projecting member carried by the hollow member at its middle and extending beyond the fixed jaw, and a pair of jaws disposed one on each side of said projection and opposed to the fixed jaw, each of said pair of jaws being pivoted to the projection and to the end of the hollow member respectively, each of the pivoted jaws having movement in an arc intersecting

the edge of the fixed jaw whereby the pivoted jaws may be moved into or out of position to wedge a curtain between the fixed jaw and the pivoted jaws.

2. A curtain support including a hollow body member comprising a top wall, a pair of side walls extending downwardly therefrom, a fixed jaw extending longitudinally of and forming a part of the body member, said jaw partially closing the space between the lower edges of the side walls, a projecting member carried centrally of the body member and extending downwardly beyond the fixed jaw, and a pair of removable jaws pivoted at their adjacent terminals to the projection and at their opposite terminals to the hollow body member, each of said movable jaws being mounted for swinging movement toward and away from the fixed jaw, whereby they may be moved into or out of position to wedge a curtain against the fixed jaw.

In testimony whereof I affix my signature in presence of two witnesses.

WLADISLAUS RAKOWSKI. [L. S.]
